UNITED STATES PATENT OFFICE

2,581,758

HARPOON CANNON

John B. Galliano, Oakland, and John R. Grigg, Alameda, Calif., assignors, by mesne assignments, to Industrial Ideas, Inc., Oakland, Calif., a corporation of California

Application August 20, 1946, Serial No. 691,724

5 Claims. (Cl. 124—11)

1
This invention relates to guns for throwing or propelling harpoons and other articles.

An object of the invention is to avoid the fire and much of the noise which accompanies the firing of a gun in which the propellant used is an explosive. Another object of the invention is to provide a gun in which the propellant does not heat the gun, so that it will not be subject, on repeated use, to the deterioration which results from the use of explosive propellants. Other objects of the invention are to provide such a gun which is durable, light in weight, simple in construction, and easy and economical to operate.

Still other objects and advantages of the invention will become apparent on reading this specification in connection with the accompanying drawings which form a part hereof.

In such drawings:

Fig. 1 is a side elevation of the gun on its mount.
Fig. 2 is a vertical, longitudinal section through the gun.

Fig. 3 is an enlargement of a portion of Fig. 2.

The gun is provided with a conventional support 11 which can be bolted or otherwise affixed to the deck or other part of a ship. The gun is mounted on the support so that it can be tilted up or down and swing about an upright axis for aiming it. The gun support and mounting are conventional and form no part of the novelty of the invention and are not described in detail.

The gun itself comprises a barrel 12, in which the projectile, for example a harpoon 13, is located. The barrel has a flange 14 which fits within the breach 16 and is held therein by an exteriorly threaded ring 17, of which the threads fit into threads on the interior of the end of the breach. The rear end of the barrel forms a valve seat 18.

A valve 19 is mounted to move toward and away from such valve seat. The valve is an operable closure for one end of a high pressure chamber 21, the other end of which is permanently closed by a wall 22. Behind this wall is another chamber 23 of somewhat less diameter than the chamber 21, so that a shoulder 24 is provided against which the wall 22 is located.

The valve 19 is mounted on a rod 26 which projects slidably through the wall 22, packing means 27 preventing leakage through the wall. The rod 26 is affixed to a piston-like member or plunger 28 which can slide back and forth in the chamber 23. It is urged forward by a spring 29, one end of which abuts against it while the other end abuts against the bottom of a cavity 31 in a plug 32 screwed into the breech. The plunger

2
28, whatever its position may be, is always spaced from the wall 22 to form a firing chamber 33 between them. The plunger 28 is provided with one or more leakage vents, as at 34, and the plug is similarly vented, as at 35. Nipples 36 and 37 connect with the chamber 21, and a nipple 38 connects with the chamber 33. A pressure gauge 39 is attached to the nipple 36. A pipe 41 is connected to a source (not shown) of gas (preferably liquid carbon dioxide) as a source of high pressure and has branches which are controlled individually by valves 42 and 43. The nipple 37 is connected by a flexible high pressure hose 44 to the branch controlled by the valve 42. Connected to the nipple 38 is a quick-acting valve 46, which, in turn, is connected by a high pressure hose 47 to the branch controlled by the valve 43. The valve 46 has an operating handle 48 which is connected by a link 49 to a trigger 51 located adjacent to an aiming handle 52. A conventional device 53 is provided to take up the recoil on firing the gun.

The operation of the invention will now be described. Valves 42 and 43 are opened before the gun is to be used. The compressed gas then flows into the high pressure chamber 21 and aids in maintaining the valve 19 closed. The trigger 51 is pulled when the gun is aimed properly with the high pressure gas in the chamber 21, and this permits high pressure gas to enter the chamber 33. This forces the plunger 28 rearwardly to exert a pull on the rod 26 and open the valve 19. One source of high pressure gas is preferred for feeding into both chambers 21 and 33, and the area of the valve 19 is made smaller than that of the plunger 28 to effect such functioning. When this valve is opened, the compressed gas rushes from the high pressure chamber 21 into the bore of the gun barrel and ejects the missile. The compressed gas in the firing chamber 33 leaks out to the atmosphere through the leakage vents 34 and 35, permitting the spring 29 to close the valve 19. Then, after properly placing another harpoon or other missile within the barrel, the gun is ready for re-use in the manner described. The pressure gauge will indicate the pressure prevailing in the propellant storage chamber 21.

The gun may be used not only for propelling harpoons but also in life saving operations at sea to send a rope or cable from one ship to another, for sending up flares, and for other purposes as well.

The bore of the gun barrel may be smooth, and the harpoon or other missile may fit the bore except for a very small tolerance of about one-sixty-

fourth ($\frac{1}{64}$) of an inch. Any suitable compressed gas may be used as the propellant, but liquid carbon dioxide is preferred as a pressure source because it is easily obtainable to produce pressures of seven hundred (700) to over one thousand (1000) pounds per square inch within the chamber 21. Pressures at least this high are preferred. With a harpoon weighing in the neighborhood of thirty-five (35) pounds, the gun is very accurate up to ranges of two hundred fifty (250) to three hundred (300) feet.

Certain details which have been referred to for the purpose of explaining the invention can be varied, added to, or omitted, without departing from the spirit of the invention, the scope of which is defined in the appended claims.

We claim:

1. A gun having a barrel and a hollow cylindrical member behind and in line therewith, a valve within the member and adjacent to the inner end of the barrel, a stem to which the valve is attached, a wall fixed within the member and spaced from the valve, the gun having a high pressure chamber formed in part by the member, valve and wall, the member having a lesser interior diameter behind the wall to form a shoulder to support the wall in position, a plunger behind the wall and movable toward and away from the wall, the stem extending through the wall and being attached to the plunger, packing to prevent leakage where the stem extends through the wall, the plunger being spaced from the wall when the valve is open and closed, the gun having a firing chamber formed in part by the member, wall and plunger, a closure member spaced from the plunger, a compression spring extending from the closure member to the plunger to close normally the valve and maintain it closed, a closed conduit to connect the high pressure chamber to a source of gas under high pressure, a valve in the conduit, a second closed conduit to connect the firing chamber to a source of gas under high pressure, a valve in the second conduit, a normally closed firing valve in the second conduit between the first mentioned valve therein and the firing chamber, and a trigger to open the last mentioned valve, the plunger and closure having vents therethrough to release pressure accumulated in the firing chamber.

2. A gun having a barrel and a pressure chamber for gas under pressure located proximately behind the barrel, a valve to selectively separate or connect the barrel and chamber, a fluid tight sealing wall closing the end of said pressure chamber opposite the said valve, a stem on which the valve is mounted, the said stem in fluid sealed relationship with and extending slidably through said wall to the outer side thereof, valve actuating means connected to said stem adjacent the outer side of said wall to urge said stem in a direction to open said valve, said valve actuating means arranged to operate independently of volume displacement of the gas contained in said pressure chamber.

3. A gun having a barrel and a pressure chamber for gas under pressure located proximately behind the barrel, a valve to selectively separate

or connect the barrel and chamber, a fluid tight sealing wall closing the end of said pressure chamber opposite the said valve, a stem on which the valve is mounted, the said stem in fluid sealed relationship with and extending slidably through said wall to the outer side thereof, and valve actuating means to open said valve operable by gas under pressure supplied from a source independent of the gas under pressure in said pressure chamber.

4. A gun having a barrel and a high pressure chamber located proximately behind the barrel, a valve to selectively separate or connect the barrel and chamber, a fluid tight sealing wall closing the end of said pressure chamber opposite the said valve, a stem on which the valve is mounted, the said stem in fluid sealed relation with and extending slidably through said wall to the outer side thereof, a plunger spaced from the outer side of said wall and connected to said valve stem, the gun having a firing chamber of which the outer side of said wall and said plunger form a part, said firing chamber being in non-fluid communication with said pressure chamber, the plunger having a greater area than the said valve, and valve means provided on said gun to supply selectively gas under pressure to said pressure chamber or said firing chamber.

5. A gun having a barrel and a high pressure chamber located proximately behind the barrel, a valve to selectively separate or connect the barrel and chamber, a fluid tight sealing wall closing the end of said pressure chamber opposite the said valve, a stem on which the valve is mounted, the said stem being in fluid sealed relation with and extending slidably through said wall to the outer side thereof, a plunger spaced from the outer side of said wall and connected to said valve stem, the gun having a firing chamber of which the outer side of said wall and said plunger form a part, said firing chamber being in non-fluid communication with said pressure chamber, the plunger having a greater area than the said valve, valve means provided on said gun to supply selectively gas under pressure to said pressure chamber or said firing chamber, and a vent provided through said plunger to release pressure accumulated in the firing chamber.
